UNITED STATES PATENT OFFICE.

VIRGINIA DAVIS, OF NEW YORK, N. Y.

KEY-RING.

1,388,100.

Specification of Letters Patent. Patented Aug. 16, 1921.

Application filed May 8, 1919. Serial No. 295,582.

To all whom it may concern:

Be it known that I, VIRGINIA DAVIS, a citizen of the United States, residing in the city, county, and State of New York, have 5 invented certain new and useful Improvements in Key-Rings, of which the following is a specification.

This invention is an improved key ring of the general character embodying a main 10 and supplemental ring, the former of which is adapted to carry a plurality of keys and the latter a single key which it is desirable to have freely accessible.

The present invention is of the same general type as described and claimed in my prior application, Serial No. 285,311, filed March 26, 1919, wherein the two loops which form the main and supplemental rings of the key ring are so associated as to lie in 20 different planes, preferably perpendicular to one another. In the said prior application both of the loops which form the key ring were made circular in shape and while this construction works out very satisfactory to hold the keys in place upon the ring, it is found that it is rather awkward to manipulate if the wire from which the ring is made is of relatively heavy gage. This is 25 due to the fact that since all parts of the ring are curvilinear in shape, the key ring affords no means for precluding the slipping of the fingers during the flexion of the main ring in attaching or detaching the keys. The object of the present invention 30 is therefore to provide a ring possessing all the advantages of the structure of the prior application, but so formed and constituted that it may be more readily manipulated without any tendency of the key ring to slip 35 from the grasp of the fingers during manipulation.

Features of the invention, other than those specified, will be apparent from the hereinafter detailed description taken in 45 conjunction with the accompanying drawings.

In the accompanying drawing I have illustrated different practical embodiments of the invention, but the constructions here- 50 in shown are to be understood as illustrative only, and not as defining the limits of the invention.

Figure 1 is a perspective view of the preferred form of the invention showing a plu- 55 rality of keys mounted on the main ring

and a single key secured to the supplemental ring.

Fig. 2 is an edge view of the key ring shown in Fig. 1 with the keys detached.

Fig. 3 shows a face view of the key ring 60 shown in Fig. 1, but with the keys removed; and.

Fig. 4 illustrates a modified ring embodying a different shape of which the invention may partake.

Referring to the drawings 1 designates the main ring and 2 the supplemental ring, both of which are formed integral from a single length of wire returned upon itself with its free ends flattened out and positioned in overlapped relation as shown. The main and supplemental rings lie in planes perpendicular to one another and are connected by a shank 3 the wires of which are substantially parallel.

When the ring is constructed as described the circumferential tension of the main loop serves to normally hold the overlapped portions of the supplemental loop in abutting relation to one another, but if it is desired 70 to position on or remove the key from the ring the main loop is flexed in a manner to decrease its diameter and by this operation the overlapped portions are forced apart to allow of the entrance or exit of the 75 key.

If the main loop 1 is made entirely circular as heretofore the flexing thereof as described is rather difficult for the reason that no part of said loop allows of a proper 80 gripping thereof by the fingers, which, because of the convex curvilinear contour of the loop allows the ring to readily slip from the grasp. For these reasons the ring of this invention is so constituted as to afford 85 a proper gripping of the ring by the fingers and this is accomplished through the shaping of the main loop in such manner that the slipping of the fingers is avoided. Dif- 90 ferent shapes of which the loop 1 may par- 95 take are shown in the Figs. 3 and 4 of the drawings, the underlying principle being 100 that the opposite sides of said loop are formed with portions which are straight or 105 concave. The form of ring shown in Figs. 1, 2 and 3 has concave sections along its 110 opposite sides which will afford a ready gripping of the ring by the fingers without slipping, whereas in Fig. 4, portions of the opposite side of the ring are made flat and

parallel, so as to enable the ring to be easily gripped by the fingers.

In forming the main loop 1 as shown in the drawing an elongated formation is im-
5 parted thereto and by such elongated for-
mation increased leverage is provided for
the flexing of said loop which renders it
more easily manipulated than would be the
case if the loop were circular. So far as the
10 present invention is concerned the parallel
sides and the concave portions may be con-
sidered as equivalents since they both assist
in the manipulation of the key ring in a
more expeditiously and facile manner than
15 heretofore.

It will be understood that mechanical and
formal changes may be made in the struc-
ture described, such as the substitution of
equivalents, without departing from the
20 spirit or substance of the invention, the
scope of which is commensurate with the
 appended claims. Moreover, the material
of which the key ring is constructed is not,
of course, limited to round wire, as it might
25 be made from wire of any suitable shape in
cross section, such as oval, rectangular or
otherwise.

Having thus fully described the inven-
tion, what I claim as new, and desire to se-
cure by Letters Patent is:

1. As a new article of manufacture, a key
ring formed from a continuous piece of wire
and embodying a main elongated loop hav-
ing certain portions of its opposite sides sub-
stantially parallel and other portions con-
cave and being provided with ends or leads
35 extending therefrom and returned upon
themselves to form a supplemental loop po-
sitioned in a plane perpendicular to the
plane of the main loop, said supplemental
loop being provided with a slit or opening
40 whereby a key may be inserted through the
slit and secured to the key ring.

2. As a new article of manufacture, a key
ring formed from a continuous piece of wire
45 and embodying main and supplemental
loops, certain complementary portions of
the opposite sides of the main loop being
parallel and other complementary portions
of the opposite sides of said loop being non-
50 parallel.

In testimony whereof, I sign my name to
this specification.

VIRGINIA DAVIS.
